UNITED STATES PATENT OFFICE.

LABAN WILSON, OF SIDNEY, WEST VIRGINIA.

TELEGRAPH-KEY.

No. 925,737.

Specification of Letters Patent.

Patented June 22, 1909.

Application filed March 11, 1908. Serial No. 420,478.

To all whom it may concern:

Be it known that I, LABAN WILSON, a citizen of the United States, residing at Sidney, in the county of Wayne and State of West Virginia, have invented new and useful Improvements in Telegraph-Keys, of which the following is a specification.

This invention relates to telegraph keys for sending messages, and relates more particularly to a key of that type provided with a switch so associated with the key that when the operator is using the key the switch or circuit closer will be opened, and upon releasing the key after sending a message will be automatically closed for completing the circuit.

The invention has for one of its objects to improve and simplify the construction and operation of apparatus of this character so as to be comparatively simple and inexpensive to manufacture, composed of few parts, and efficient and reliable in use.

A further object of the invention is the provision of a telegraph key provided with a secondary lever disposed over the lever of the key and arranged to automatically open and close the circuit upon gripping or releasing the key in the sending of a message.

30 A further object of the invention is the provision of an adjustable contact element mounted on the secondary lever and adapted to engage a fixed contact on the metallic frame of the key.

35 With these objects in view and others, as will appear as the description proceeds, the invention comprises the various novel features of construction and arrangement of parts which will be more fully described 40 hereinafter and set forth with particularity in the claims appended hereto.

In the accompanying drawing, which illustrates one of the embodiments of the invention, Figure 1 is a vertical longitudinal section of the device. Fig. 2 is a plan view thereof. Fig. 3 is a section on line 3—3, Fig. 1.

Similar reference characters are employed to designate corresponding parts throughout the several views.

Referring to the drawings, A designates a suitable base-plate on which is mounted the metallic frame B of the device, the said frame consisting of a bottom plate 1 and 55 upwardly-extending parallel arms or posts

2. Mounted between the posts is the main lever 3 of the key, the said lever being pivoted in the usual manner in set screws. One end of the key is provided with a button 4 whereby the operator can conveniently 60 take hold of the same for sending a message, the opposite end of the lever being provided with the usual adjustable stop screw 5. On the bottom side of the lever is a platinum or other contact 6 arranged in coöperative 65 relation with the stationary contact 7 to engage the latter in completing the circuit during the sending of the message, the contact 7 being mounted on a metallic stud 8 secured in fixed position on the base-plate 70 A by a screw 9 and insulated from the bottom plate 1 by a bushing 10 of insulation. Interposed between the lever 3 and bottom plate 1 is a spring 11 which is adjusted by a screw 12 carried by the lever and which 75 maintains the contacts 6 and 7 separated when the instrument is not in use.

Disposed over the lever 3 is a secondary lever 13 which is formed with pivots 14 that, like the pivots of the lever 3, bear in set 80 screws 15 carried by the posts 2, the set screws being held in adjusted position, by clamping nuts 16. The lever 13 is provided with an opening 17 through which the spring-adjusting screw 12 extends so as 85 to enable the head of the screw to be readily grasped for adjusting the spring, and on the lever 13 is an adjusting screw 18 threaded in said lever and arranged to adjust the tension of the spring 19. This spring passes 90 through an opening 20 in the main lever 3 and bears on the bottom plate 1 of the frame B so as to normally hold the secondary lever in closed circuit position. On the rear end of the lever 13 is a contact element 21 of a 95 circuit closer C. The element 21 in the present instance consists of a yoke 22 having depending arms 23 that span the rear end of the lever 3 and are adapted to normally engage a stationary contact 24. On the lever 13 is a yoke 25 that is disposed over the yoke 22 and adjustably carries the latter by means of set screws 26 whereby the contact element 21 can be accurately adjusted with respect to the stationary contact 24 and the set 100 screws are retained in adjusted position by clamping nuts 27. In the present instance, the stationary contact 24 is in the form of a wire 28 that is connected with studs 29 which 105 pass through openings 30 in the bottom plate 110

1 and base plate A, as clearly shown in Fig. 3, and these studs are provided with insulating bushings 31. The screws 32 of the studs are connected by a wire 32' with the 5 screw 9 of the stud 8. The key is connected to the two sides *a* and *b* of the circuit in any desired manner, as for instance by the screw 34 connecting the wire *a* with the plate 1, and the screw 9 connecting the wire *b* with 10 the stud 8.

In practice, when the instrument is idle, the parts are in the position shown in Fig. 1, the circuit closer C being in closed position so that the telegraph circuit will be in normal condition. When the operator desires 15 to send a message, he grips the button 4 and at the same time places one finger on the button 33 of the secondary lever and holds the latter depressed against the button 4 as he 20 manipulates the lever 3 for sending a message. As soon as the message is completed, he releases the instrument and the levers immediately return to normal position, whereby the circuit will be completed by 25 the circuit closer C.

From the foregoing description, taken in connection with the accompanying drawing, the advantages of the construction and of the method of operation will be readily 30 apparent to those skilled in the art to which the invention appertains, and while I have described the principle of operation of the invention, together with the apparatus which I now consider to be the best embodiment 35 thereof, I desire to have it understood that the apparatus shown is merely illustrative, and that such changes may be made when desired as are within the scope of the claims.

Having thus described the invention, what 40 I claim is:—

1. In a telegraph key, the combination of a supporting frame, a key lever fulcrumed thereon, a circuit closing lever fulcrumed on the frame at a point above the key lever, 45 and sets of contacts arranged to open and close the circuit by the movement of the levers, the set of contacts for one lever being located forwardly of the fulcrum of the

latter and the set for the other lever being located rearwardly of its fulcrum. 50

2. In a telegraph key, the combination of a supporting frame, a key lever mounted thereon, a secondary lever disposed over the key lever, a fixed contact on the frame, a contact on the secondary frame and consisting of spaced members disposed in coöperative relation with the fixed contact, and separate devices supporting the said contact on the secondary lever for adjusting the members to both engage the fixed contact. 60

3. In a telegraph key, the combination of a supporting frame, a lever fulcrumed thereon and provided with an aperture, a spring disposed between the frame and lever, means on the lever for adjusting the 65 spring, a secondary lever having an aperture for receiving the said means, a spring passing through the aperture of the first-mentioned lever and arranged to hold the secondary lever in normal position, contacts 70 arranged to open and close the circuit by the movement of the first lever, and a circuit closer controlled by the secondary lever.

4. In a telegraph key, the combination of a supporting frame, a main lever mounted 75 thereon, a secondary lever, a wire arranged on the supporting frame to form a stationary contact, an adjustable contact on the secondary lever and arranged to engage the said wire, and a screw supporting and adjusting the last-mentioned contact on the secondary lever.

5. In a telegraph key, the combination of a main lever, a secondary lever, a cross-piece on the secondary lever, a yoke having members straddling the first lever, means for adjustably connecting the yoke with the cross-piece, and a stationary contact arranged in coöperative relation with the said members. 85

In testimony whereof I affix my signature 90 in presence of two witnesses.

LABAN WILSON.
